UNITED STATES PATENT OFFICE.

JAMES B. SEAGER, OF LANSING, MICHIGAN.

CARBURETER.

984,032.

Specification of Letters Patent. Patented Feb. 14, 1911.

Application filed January 27, 1908. Serial No. 412,824.

To all whom it may concern:

Be it known that I, JAMES B. SEAGER, a citizen of the United States of America, residing at Lansing, State of Michigan, have 5 invented certain new and useful Improvements in Carbureters, of which the following is a specification, reference being had therein to the accompanying drawings.

The invention relates to carbureters designed for use in connection with explosion engines and of the type provided with a reservoir for the liquid fuel, and in which a substantially constant level is maintained. Heretofore various constructions of carbureters of this type have been devised which have been provided with means for maintaining a constant level in the reservoir such, for instance, as float controlled valves for regulating the supply. Other constructions 20 have been provided with mechanically actuated pumps for supplying the liquid fuel to the reservoir with an overflow and return connection for the propelled fuel.

It is the object of the present invention to 25 obtain a construction in which a constant level is permanently and automatically maintained in the reservoir without necessitating either float valves, mechanical pumps, or other mechanically actuated mechanism 30 for controlling the supply.

To this end the invention consists in the construction in which the liquid fuel is drawn into the reservoir by suction from the carbureter or its actuating means, such as 35 the engine, to which it is attached, and further in the peculiar construction and arrangement of parts as hereinafter set forth.

In the drawings my improvement is illustrated diagrammatically in vertical central section, in which A represents a carbureter of any suitable construction, B the suction conduit leading to the engine or other suction means, C the discharge nozzle for the 45 liquid fuel, and D the reservoir for supplying fuel to said nozzle.

In the diagrammatic illustration, the reservoir D is shown at one side of the carbureter casing, and such a construction may be employed if desired, or the reservoir may be 50 arranged to surround the carbureter casing as is common with carbureters of this type.

E is the supply tank for the liquid fuel 55 vented by means of the port E'. This tank with carbureters in which the supply is controlled by a float valve is necessarily placed

at a higher level than the reservoir D, but it is usually more convenient to place the tank at a lower level, which is permitted by my construction.

F is a conduit leading from the bottom of the supply tank E into the reservoir D, and G is a check valve in this pipe for preventing return of the liquid from the reservoir to the tank. The reservoir D is divided 60 into two compartments by a partition H, and the height of this partition is such as to maintain a level of the liquid in one compartment I preferably but slightly lower than the discharge end of the nozzle C. The 65 surplus fluid in the compartment I will flow over the top of the partition H into the compartment J from which it is returned through a conduit K to the tank E.

For causing the flow of the liquid fuel 70 through the conduit F a suction connection is provided for the reservoir D and, as shown, this consists of a conduit L connecting the upper portion of the reservoir D with the interior of the carbureter casing A. 75 This will result in producing a partial vacuum in the reservoir D during each suction stroke of the engine permitting atmospheric pressure upon the liquid in the tank E to force a flow upward through the conduit F and into the compartment I. With 80 the restoration of the normal pressure in the reservoir D, the flow through the conduit F ceases, but the check valve G prevents the return of the fluid in said conduit. 85 The surplus fluid supplied to the compartment I will overflow the partition H, and will be returned by gravity through the conduit K to the tank E. This conduit K also 90 contains a check valve M which closes during the suction stroke and prevents the drawing of the liquid upward through the conduit K.

The above described construction is entirely automatic in its operation, as has been 100 set forth, and is one which dispenses with all mechanically actuated mechanisms for forcing or controlling the supply of the liquid fuel.

As in the operation of the carbureter, a 105 liquid is discharged from the nozzle C by the differential pressure, it is necessary that the pressure upon the surface of the liquid in the reservoir D should be greater than at the discharge end of the nozzle. This 110 is accomplished with the specific construction shown by arranging the discharge

nozzle in a contracted portion of the suction conduit, while the connection L to the reservoir D is in the expanded portion of said conduit. Thus while both the carbureter and the reservoir are simultaneously connected to the same source of suction there will always be the necessary differential pressure to feed the oil.

What I claim as my invention is:

- 10 1. The combination with a carbureter of the suction type, of a reservoir for supplying liquid thereto, a discharge connection between the reservoir and the carbureter, and means for supplying liquid to said reservoir solely by the suction of the suction producing means of the carbureter.
- 15 2. The combination with a carbureter of the suction type, of a reservoir for liquid, a discharge conduit leading from said reservoir to said carbureter, a conduit for supplying liquid to said reservoir from a source at a lower level, and means for feeding the liquid through said supply conduit by the suction of the suction producing means of the carbureter.
- 20 3. The combination of a reservoir, a conduit for supplying liquid therefrom to a carbureter, a conduit for supplying liquid to said reservoir from a source at a lower

level and suction means for simultaneously causing a flow of the liquid through the supply conduit to said reservoir and the discharging of the liquid from said reservoir to said carbureter.

4. The combination with a carbureter of the suction type, of a reservoir for supplying liquid thereto, and means operated solely by the suction of the carbureter for supplying and discharging liquid to and from said reservoir.

5. The combination with a carbureter of the suction type, of a reservoir for liquid, a discharge conduit leading from said reservoir to said carbureter, a conduit for supplying liquid to said reservoir from a source at a lower level, and means for feeding the liquid through said supply conduit by the suction of the suction producing means of the carbureter comprising a conduit connecting said reservoir with the suction means, for the purpose described.

In testimony whereof I affix my signature in presence of two witnesses.

JAMES B. SEAGER.
